(57) **ABSTRACT**

A force reducing device and method for adjusting shutter ropes is provided wherein winding boxes are divided into two sets. Two winding box sets are symmetrically disposed with respect to a center of the upper beam, and each winding box set is fixed with a rope. The two ropes pass through respective holes in the slats, and then wind through a first pulley on the lower beam, and then extend and wind through a second pulley. The two ropes pass upwardly through the respective hole in the slats. Then, the two ropes pass through the outlets of the balance strip and are combined as a first combined rope. The first combined rope passes through an opening of the rope retaining seat to be combined with opposing ends of another rope.

**FORCE REDUCING DEVICE AND METHOD
FOR ADJUSTING SHUTTER ROPES**

FIELD OF THE INVENTION

The present invention relates to a force reducing device for adjusting shutter ropes, wherein, in addition to pulling a shutter with less force, the shutter can be assembled easily.

BACKGROUND OF THE INVENTION

Shutters of large size cannot be used to replace cloth window curtains due to the large force necessary to operate the rope of the shutters. The current force reducing device for shutters has pulleys in the lower beam thereof. The ropes pass through the same holes in the slats, so that the holes must be elongated. In addition to being difficult to assemble, the strength of each of the slats is weakened. In order to reduce the required force, the length of the rope must be elongated in an inverse ratio to the amount of force reduction. However, a long rope spoils the appearance of the shutters. Furthermore, the operation of those shutters is inconvenient.

SUMMARY OF THE INVENTION

Accordingly, the primary object of the present invention is to provide a force reducing device for adjusting shutter ropes, wherein, in addition to pulling shutter ropes with less force, the shutters can be assembled easily.

To achieve that object, the present invention provides a force reducing device, for adjusting shutter ropes and the method thereof.

An upper beam is embedded with a plurality of pulley boxes, a slat angle drive, a plurality of winding boxes and a rope retaining seat. Each winding box has a rolling shaft. The rope retaining seat has a balance strip. A lower beam has a plurality of holes and a plurality of pulleys. A plurality of slats each have holes formed therethrough. The winding boxes are divided into two sets. The two winding box sets are symmetrically arranged with respect to a center of the upper beam, and each winding box set is fixed with a respective rope. The two ropes pass through respective holes in the slats, and then wind through a first pulley on the lower beam. Then, the ropes extend and wind through a second pulley of the same set with the first pulley on the lower beam. The two ropes then pass upwards through the respective holes on the slats, and then pass through the upper sides of a rolling shaft below the winding boxes. The two ropes pass through outlets at an upper and a lower side of the balance strip, and then the two ropes are combined as a first combined rope. Then, the first combined rope passes through an opening at another side of the rope retaining seat to be coupled to opposing ends of another rope to form a second combined rope. When the second combined rope is pulled, one end of the rope will lift the shutter, and another end of the rope will be received in an inner space of the upper beam.

The various objects and advantages of the present invention will be more readily understood from the following detailed description when read in conjunction with the appended drawings.

BRIEF DESCRIPTION OF THE DRAWINGS

FIG. 1 is an exploded perspective view of a first preferred embodiment of the present invention.

FIG. 2 is a schematic view of the path of the rope of FIG. 1.

FIG. 3 is a schematic perspective view showing that two pulleys of the lower beam of FIG. 1 are formed as one set.

FIG. 4 is a left side view of FIG. 3.

FIG. 5 is an exploded perspective view of the second preferred embodiment of the present invention.

FIG. 6 is a schematic perspective view showing that two pulleys of the lower beam of FIG. 5 are formed as one set.

FIG. 7A shows a left side view of FIG. 6.

FIG. 7B shows a right side view of FIG. 6.

FIG. 8 is a schematic perspective view of a plug.

FIG. 9 is an exploded cross sectional view of the third preferred embodiment of the present invention.

FIG. 10 is a schematic perspective view showing that two coupling means of FIG. 9 are formed as one set.

FIG. 11 is a left side view of the coupling means in the third embodiment.

FIG. 12 is a schematic perspective view of the plug in the third embodiment.

FIG. 13 is an exploded schematic view of the fourth preferred embodiment of the present invention.

FIG. 14 is a schematic perspective view showing that two coupling means of FIG. 13 are formed as one set.

FIG. 15A is a left side view of a coupling means in the fourth embodiment.

FIG. 15B is a right side view of another coupling means in the fourth embodiment.

FIG. 16A is a perspective view of a winding box 31 of the present invention.

FIG. 16B is a schematic cross sectional view along line 16B—16B of the winding box 31 of FIG. 16A.

FIG. 17A is a perspective view of a winding box 32 of the present invention.

FIG. 17B is a schematic cross sectional view along line 17B—17B of the winding box 32 of FIG. 17A.

FIG. 18A is a perspective view of a winding box 33 of the present invention.

FIG. 18B is a schematic cross sectional view along line 18B—18B of the winding box 33 of FIG. 18A.

FIG. 19A is a perspective view of a winding box 34 of the present invention.

FIG. 19B is a schematic cross sectional view along line 19B—19B of the winding box 34 of FIG. 19A.

FIG. 20 is a schematic perspective view of one slat in the present invention.

DETAILED DESCRIPTION OF THE PREFERRED EMBODIMENTS

In order that those skilled in the art can further understand the present invention, the invention will be described in the following detailed description. However, these descriptions and the appended drawings are provided to aid those skilled in the art to understand the objects, features, and characteristics of the present invention, but should not be used to confine the scope and spirit of the present invention defined in the appended claims.

Referring to FIGS. 1, 2, 16A, 16B, 17A, 17B, 18A, 18B, 19A and 19B, the upper beam 5 is sequentially embedded with a pulley box 1, a slat angle drive 2, a winding box 31, a winding box 32, a winding box 33, a winding box 34, and a rope retainer 4. The pulley box 1 is installed with a pulley 1a. The slat angle drive has a guide groove 21, a guide groove 22, a hook 23, a rotary rod 24 and a link shaft 25.

penetrating through the winding box 31, winding box 32, winding box 33 and winding box 34.

The winding box 31 is installed with a guide groove 311, a guide groove 312, a guide groove 313, and a rolling shaft 31a. The winding box 32 is installed with a guide groove 321, guide groove 322, guide groove 323, and rolling shaft 32a. The winding box 33 is installed with a guide groove 331, a guide groove 332, a guide groove 333, and a rolling shaft 33a. The winding box 34 is installed with a guide groove 341, a guide groove 342, a guide groove 343, and a rolling shaft 34a.

The rope retainer 4 is formed with an opening 41, and an opening 42, a balance strip 43, an outlet 44, a fixing wheel 45 and a fixing wheel 46.

The ladder rope 11, ladder rope 12, ladder rope 13 and ladder rope 14 respectively pass by the slats 61, 62, 63, 64, 65 and 66. The upper ends of the ladder rope 11, ladder rope 12, ladder rope 13 and ladder rope 14 respectively pass through the hole 5a, hole 5c, hole 5d, hole 5f, hole 5g, hole 5i, hole 5j and hole 5l of the upper beam 5 to be respectively fixed to the winding box 31, winding box 32, winding box 33, and winding box 34. The lower ends thereof are fixed to the holes of the lower beam 7x corresponding to the winding box 31, winding box 32, winding box 33, and winding box 34, by the plug 91, plug 92, plug 93 and plug 94. The shaft 811, shaft 821, shaft 831, and shaft 841 pass through the pulley 810, pulley 820, pulley 830, and pulley 840 and are fixed to the lower beam 7x.

The winding box 31 and winding box 32 define one set and winding box 33 and winding box 34 define another set. The rope 15 is fixed to the rolling shaft 32a of the winding box 32 and then passes downwards through the hole 5e and openings in the slat 61, slat 62, slat 63, slat 64, slat 65 and slat 66, at positions corresponding to the hole 5e. Then, it winds through the right side of the pulley 820 in the lower beam 7x and then passes over pulley 810 and through respective holes in the slat 61, slat 62, slat 63, slat 64, slat 65 and slat 66 corresponding to the hole 5b. Then the rope passes through the hole 5b to the rolling shaft 31a, guide groove 313, guide groove 323, guide groove 333, and guide groove 343 to the outlet 44 of the rope retaining seat 4. The rope 16 is fixed to the rolling shaft 33a of the winding box 33, and then passes through the holes 5h and corresponding holes of slat 61, slat 62, slat 63, slat 64, slat 65 and slat 66. Then, it passes over the left side of the pulley 830 on the lower beam 7x to the right side of the pulley 840. The rope 16 then passes upwards through corresponding holes of the slat 61, slat 62, slat 63, slat 64, slat 65 and slat 66, and through the hole 5k. Then, the rope 16 passes through the rolling shaft 34a, and guide groove 343 of the winding box 34 to the outlet 44 of the rope retaining seat 4.

The rope 15 and rope 16 are combined and fixed together external to the outlet 44. The extension of the combined ropes 15 and 16 are combined with a rope 17. The rope 17 passes through the opening 42 to enter into the upper beam 5. Then it passes through the guide groove 341, guide groove 331, guide groove 321, guide groove 311, and guide groove 21 to pass over the pulley 1a and then it passes through the guide groove 22, guide groove 312, guide groove 322, guide groove 332, and guide groove 342. Then, the rope 17 passes out through the opening 41 and passes through the fixing ring 47 with the opposing end of the rope 17 and ropes 15 and 16, and is combined therewith.

When the fixing ring 47 or the rope 17 below the fixing ring 47 is pulled leftwards and downwards, the rope 15, rope 16 and rope 17 are also pulled. The rope 15 and 16 lift the

lower beam (shutter) upwards. The rope 17 stores the rope 15 and rope 16 in the inner space of the upper beam 5, along the periphery of the upper beam 5. If the rope 17 is released rightwards and upwards, then the rope 15 and rope 16 are buckled between the fixing wheel 45 and fixing wheel 46. Therefore, in addition to force being reduced and being easily assembled, the rope is stored.

With reference to FIGS. 3 and 4, in the lower beam 7x the pulley 810 and pulley 820 define one set and are installed with an upper left panel 71, an upper right panel 72, a left panel 73, a hole 73a, a right panel 74, a hole 74a, a hole 74b, a hole 75a, and a hole 75b. The shaft 811 and shaft 821 respectively pass through the pulley 810 and pulley 820 to be fixed to the lower beam 7x. The rope 15 winds downwards over the right side of the pulley 820 and upwards from the left side of the pulley 810. The hole 75a and hole 75b on the bottom plate 75 respectively receive plug 91 and plug 92 therein to fix the ladder rope 11 and ladder rope 12 in the lower beam 7x. The upper left panel 71 and upper right panel 72 can support the weight of the slat 61, slat 62, slat 63, slat 64, slat 65 and slat 66 without deformation.

Referring to FIGS. 5, 6, 7A and 7B, FIG. 5 is an exploded perspective view of the second preferred embodiment of the present invention. The difference of this embodiment from the first embodiment is that the structure of the lower beam 7y is different from the lower beam 7x, while the other parts are identical.

In the lower beam 7y, the pulley 810 and pulley 820 are formed as one set and have an upper left panel 7a, a flange 7a1, an upper right panel 7b, a flange 7b1, a middle plate 7e, a bottom plate 7d, a hole 7d1, a hole 7d2, plug 71a, a flange 71a1, a plug 71b, a flange 71b1, an opening 714, and opening 715, a plug 72a, a flange 72a1, a plug 72b, a flange 72b1, an opening 724, and an opening 725. The rope 15 passes downwards through the right side of the pulley 820 and then passes upwards from the left side of the pulley 810. The hole 7d1 and hole 7d2 on the bottom plate 7d respectively receive the plug 91 and plug 92 to fix the ladder rope 11 and ladder rope 12 in the lower beam 7y. The upper left panel 7a and upper right panel 7b can support the weight of the slat 61, slat 62, slat 63, slat 64, slat 65 and slat 66 without deformation. In addition to increasing the strength of the lower beam 7y, the middle plate 7c has the function of fixing the plug 71a, plug 71b, plug 72a and plug 72b.

In assembly, the shaft 811 and shaft 821 pass through the pulley 810 and pulley 820 and then enters into the lower side of the upper left panel 7a and upper right panel 7b through the opening 714, opening 715, opening 724 and opening 725. Then, the plug 71a, plug 71b, plug 72a and plug 72b are each respectively inserted into the opening 714, opening 715, opening 724 and opening 725. The flange 7a1, flange 7b1, flange 71a1, flange 71b1, flange 72a1, and flange 72b1 servo to retain the shaft 811 and shaft 812 in proper positions in the lower beam 7y.

The shaft 831 and shaft 841 respectively pass through the pulley 830 and pulley 840 and enter into the lower beam 7y to form another set. The structure is identical to the set formed by the pulley 810 and the pulley 820.

As shown in FIG. 8, a schematic perspective view of the plug 91 is illustrated. The plug 91 has a round cylinder 911, a groove 911a, a groove 911b, and a round sleeve 912. The structures of the plug 92, plug 93, and plug 94 are identical to that of the plug 91.

Referring to FIGS. 9, 10, 11, and 12, FIG. 9 is an exploded perspective view of another preferred embodiment of the present invention. The difference of FIG. 9 from the first

embodiment illustrated in FIG. 1 is that the lower beam 7 has a coupling means 81, a coupling means 82, a coupling means 83 and a coupling means 84 which are coupled thereon. The other parts are identical.

In the lower beam 7, the coupling means 81 and the coupling means 82 are formed as at set and have a pulley 810, a shaft 811, a shaft 812, an upper left panel 81a, an upper right panel 81b, a left panel 81c, a hole 81c1, a hole 81c2, a right panel 81d, a hole 81d1, a hole 81d2, a bottom plate 81e, a hole 81e1, a pulley 820, a shaft 821, a shaft 822, an upper left panel 82a, an upper right panel 82b, a left panel 82c, a right panel 82d, a hole 82d1, a hole 82d2, a bottom plate 82e, a hole 82e1, etc. The bottom of the lower beam 7 has a hole 713, a hole 723, a hole 733 and a hole 743 with respect to a coupling means 81, a coupling means 82, a coupling means 83 and a coupling means 84. The hole 713 and hole 723 are respectively located with respect to the hole 81e1, and the hole 81e2 on the bottom plate 81e and bottom plate 82a, at the bottom of the coupling means 81 and coupling means 82. The holes 713 and 723, and holes 81c1 and 81c2 can respectively receive the plug 91a and plug

92a, so that the ladder rope 11 and ladder rope 12 are fixed in the lower beam 7, and the coupling means 81 and coupling means 82 are fixed on the lower beam 7. The shaft 811 and shaft 821 respectively pass through the pulley 810 and pulley 820 and then are fixed to the coupling means 81 and coupling means 82. The rope 15 winds through the right side of the pulley 820 and then passes upwards from the left side of the pulley 810. The shaft 812 penetrates through the hole 81d1 and hole 912a, hole 81c2 and the lower beam 7 for enhancing the coupling between the coupling means 81 and lower beam 7. Similarly, the coupling means 82, coupling means 83 and coupling means 84 have respective shafts passing through the lower beam 7, plug 92a, plug 93a and plug 94a to enhance the coupling between the coupling means 82, coupling means 83, coupling means 84 and lower beam 7.

The upper left panel 81a, upper right panel 81b, upper left panel 82a, and upper right panel 82b can support the weights of the slat 61, slat 62, slat 63, slat 64, slat 65 and slat 66 without deformation.

The coupling means 83 and coupling means 84, which are formed as another set, have the same structure, and principle as the set formed by the coupling means 81 and coupling means 82.

FIG. 12 is a schematic perspective view of the plug 91a. The plug 91a has a round cylinder 911, a groove 911a, groove 911b, a round sleeve 912, and a hole 912a. The hole 912a penetrates through the round sleeve 912. The structures of the plug 92a, plug 93a, and plug 94a are identical to that of the plug 91a.

As shown in the FIGS. 13, 14, 15A and 15B, FIG. 14 is an exploded perspective view of the fourth preferred embodiment of the present invention. The difference of this embodiment from the first embodiment illustrated in FIG. 1 is that the lower beam 7 has a coupling means 8a, a coupling means 8b, a coupling means 8c and a coupling means 8d which are coupled thereon. The other parts are identical.

In the lower beam 7, the coupling means 8a and coupling means 8b are formed as a set and have an upper left panel 8a1, a flange 8a11, a stopper 8a12, an upper right panel 8a2, a flange 8a21, a stopper 8a22, a middle plate 8a3, a bottom plate 8a4, a hole 8a41, a hole 8a5, a plug 8a6, a groove 8a61, a groove 8a62, a flange 8b21, a stopper 8b22, at middle plate 8b3, at bottom plate 8b4, a hole 8b41, a hole 8b5, a plug 8b6, a groove 8b61, a groove 8b62, a pulley 810,

a shaft 811, a pulley 820, a shaft 821, etc. The bottom of the lower beam 7 has a hole 713, a hole 723, a hole 733 and a hole 743 disposed in respective correspondence to the bottoms of the coupling means 8a, coupling means 8b, coupling means 8c and coupling means 8d. The shaft 811 and shaft 821 respectively pass through the pulley 810 and pulley 820 and then enter into the coupling means 8a and coupling means 8b along the space between the middle plates 8a3 and 8b3 and flanges 8a11 and 8a21 of the coupling means 8a and coupling means 8b. Then, they are retained in the selected positions in the coupling means 8a and coupling means 8b by the stopper 8a12, stopper 8a22, stopper 8b12, and stopper 8b22. The hole 713 and hole 723 are respectively disposed with respect to the hole 8a41 and hole 8b41 in the bottom plate 8a4 and bottom plate 8b4, at the bottoms of the coupling means 8a and coupling means 8b. The holes 713 and 723 and 8a41 and 8b41 respectively receive the plug 91 and the plug 92, to fix the ladder rope 11 and ladder rope 12 in the lower beam 7 and then fix the coupling means 8a and coupling means 8b on the lower beam 7. The rope 15 winds downwards through the right side of the pulley 820 and then passes upwards from the left side of the pulley 810. The upper left panel 8a1, upper right panel 8a2, upper left panel 8b1, and upper right panel 8b2 can support the weight of the slat 61, slat 62, slat 63, slat 64, slat 65 and slat 66 without deformation.

The coupling means 8c and coupling means 8d which are formed as another set have the same structure and principle as the set formed by the coupling means 8a and coupling means 8b.

A schematic perspective view of tie slat 61 is illustrated in FIG. 20. The slat 61 has hole 611, hole 612, hole 613 and hole 614 which form channels for the rope 15 and rope 16. Similarly, the slat 62, slat 63, slat 64, slat 65, slat 66 have corresponding holes.

By the above structure of the present invention, and in its practical utilization, the number of winding boxes of each rope set can be changed with respect to the number of winding boxes in each product. If the number of winding boxes is six, then the first, second and third winding boxes are defined as one set, and the fourth, fifth and sixth winding boxes are defined as another set. The space for receiving the ropes can be installed in any space, such as the upper side or lower side or front side or the rear side of the upper beam. The constructions are identical to the previously described embodiment.

From the description of the present invention, as thus described, it will be obvious that the same may be varied in many ways. Such variations are not to be regarded as a departure from the spirit and scope of the present invention, and all such modifications as would be obvious to one skilled in the art are intended to be included within the scope of the following claims.

What is claimed is:

1. A force reducing device for adjusting shutter ropes comprising:
an upper beam;
a pulley box coupled to one end of said upper beam, said pulley box including a first pulley rotatably mounted therein;
a rope retaining seat coupled to an opposing end of said upper beam, said rope retaining seat including a balance strip having outlets formed therein;
a slat angle drive mounted to said upper beam and having a link shaft extending therefrom;
a plurality of winding boxes mounted to said upper beam and respectively coupled to said link shaft, each of said

winding boxes having a rolling shaft, said plurality of winding boxes being divided into two sets of winding boxes, said two sets of winding boxes being symmetrically disposed with respect to a center of said upper beam, a first of said two sets of winding boxes having a first rope fixed thereto and a second of said two sets of winding boxes having a second rope fixed thereto; a lower beam having a plurality of second pulleys mounted therein, said lower beam having a plurality of holes formed therethrough; a plurality of slats disposed between said upper beam and said lower beam and supported by a plurality of ladder ropes, each of said slats having a plurality of openings formed therethrough; a third rope having one portion thereof passing through 15 said rope retaining seat to extending through said upper beam and pass around said first pulley of said pulley box, said third rope having another portion extending from said first pulley back through said upper beam to pass back through said rope retaining seat; and, 20 a fixing ring securing opposing ends of said third rope to form a continuous loop with a portion thereof having a predetermined length extending from said rope retaining seat, said first and second ropes respectively extending downwardly from a respective winding box 25 of said two sets of winding boxes, said first and second ropes respectively passing through first corresponding openings of said plurality of slats to extend around a respective pair of said plurality of second pulleys and pass upwardly through second corresponding openings 30 of said plurality of slats to extend over a respective one of said rolling shafts, said first and second ropes having respective end portions extending from said respective rolling shafts through corresponding outlets of said balance strip, said end portions of said first and second 35 ropes being joined together with said opposing ends of said third rope by said fixing ring, wherein displacement of a length of said joined first, second and third ropes from said rope retaining seat to raise said lower beam is matched by a corresponding length of said 40 third rope being displaced into said upper beam to thereby maintain said predetermined length of said portion of said continuous loop substantially unchanged.

2. The force reducing device for adjusting shutter ropes as 45 recited in claim 1, wherein said lower beam is a tube having an elongated opening at an upper side thereof; a plurality of fixing shafts fixed to said lower beam respectively pass through said plurality of second pulleys; said lower beam having a plurality of holes formed through a bottom thereof; 50 said force reducing device further comprising a plurality of plugs respectively inserted into said holes in said bottom of said lower beam for respectively fixing said plurality of ladder ropes to said lower beam.

3. The force reducing device for adjusting shutter ropes as 55 recited in claim 1, wherein said lower beam is a tube having an elongated opening at an upper side thereof for said first and second ropes to pass therethrough, said lower beam including an enhancing spacer disposed adjacent a lower side of said elongated opening; a plurality of fixing shafts fixed to 60 said lower beam through a plurality of small openings formed therein, said plurality of fixing shafts respectively pass through said plurality of second pulleys; said force reducing device further comprising a plurality of plugs respectively inserted into said holes in said bottom of said 65 lower beam for respectively fixing said plurality of ladder ropes to said lower beam.

4. The force reducing device for adjusting shutter ropes as recited in claim 1, wherein said slat angle drive and each of said winding boxes have guide grooves formed in opposing sides thereof for respective portions of said third rope to extend therethrough.

5. A force reducing device for adjusting shutter ropes comprising:

- an upper beam;
- a pulley box coupled to one end of said upper beam, said pulley box including a first pulley rotatably mounted therein;
- a rope retaining seat coupled to an opposing end of said upper beam, said rope retaining seat including a balance strip having outlets formed therein;
- a slat angle drive mounted to said upper beam and having a link shaft extending therefrom;
- a plurality of winding boxes mounted to said upper beam and respectively coupled to said link shaft, each of said winding boxes having a rolling shaft, said plurality of winding boxes being divided into two sets of winding boxes, said two sets of winding boxes being symmetrically disposed with respect to a center of said upper beam, a first of said two sets of winding boxes having a first rope fixed thereto and a second of said two sets of winding boxes having a second rope fixed thereto;
- a lower beam having a plurality of holes formed therethrough;
- a plurality of couplings mounted to said lower beam in respective correspondence to said plurality of winding boxes, said plurality of couplings respectively having a plurality of second pulleys mounted thereto;
- a plurality of slats disposed between said upper beam and said lower beam and supported by a plurality of ladder ropes, each of said slats having a plurality of openings formed therethrough;
- a third rope having one portion thereof passing through said rope retaining seat to extending through said upper beam and pass around said first pulley of said pulley box, said third rope having another portion extending from said first pulley back through said upper beam to pass back through said rope retaining seat; and,
- a fixing ring securing opposing ends of said third rope to form a continuous loop with a portion thereof having a predetermined length extending from said rope retaining seat, said first and second ropes respectively extending downwardly from a respective winding box of said two sets of winding boxes, said first and second ropes respectively passing through first corresponding openings of said plurality of slats to extend around a respective pair of said plurality of second pulleys and pass upwardly through second corresponding openings of said plurality of slats to extend over a respective one of said rolling shafts, said first and second ropes having respective end portions extending from said respective rolling shafts through corresponding outlets of said balance strip, said end portions of said first and second ropes being joined together with said opposing ends of said third rope by said fixing ring, wherein displacement of a length of said joined first, second and third ropes from said rope retaining seat to raise said lower beam is matched by a corresponding length of said third rope being displaced into said upper beam to thereby maintain said predetermined length of said portion of said continuous loop substantially unchanged.

6. The force reducing device for adjusting shutter ropes as recited in claim 5, wherein each of said plurality of couplings are formed by a short tube having an elongated opening at an upper side thereof of passage of a respective one of said first and second ropes therethrough, each said coupling having a bottom with a hole formed therethrough in correspondence to a respective hole formed through a bottom of said lower beam; said force reducing device further comprising a plurality of plugs respectively inserted into said holes in said bottom of said couplings and said bottom of said lower beam for respectively fixing said plurality of ladder ropes to said lower beam. 5

7. The force reducing device for adjusting shutter ropes as recited in claim 5, wherein each of said plurality of couplings are formed by a short tube having an elongated 15 opening at an upper side thereof of passage of a respective one of said first and second ropes therethrough, each said coupling having a bottom with a hole formed therethrough in correspondence to a respective hole formed through a bottom of said lower beam; said force reducing device 20 further comprising a plurality of plugs respectively inserted into said holes in said bottom of said couplings and said bottom of said lower beam for respectively fixing said plurality of ladder ropes to said lower beam; each of said couplings including a fixing shaft secured thereto and passing 25 through said second pulley thereof.

8. The force reducing device for adjusting shutter ropes as recited in claim 5, wherein said slat angle drive and each of said winding boxes have guide grooves formed in opposing sides thereof for respective portions of said third rope to 30 extend therethrough.

9. A force reducing method for adjusting shutter ropes, comprising the step of:

providing an upper beam;

coupling a pulley box having a first pulley, a slat angle 35 drive, a plurality of winding boxes, and a rope retaining seat to said upper beam, each of said plurality of winding boxes including a rolling shaft and said rope retaining seat including a balance strip;

dividing said plurality of winding boxes into two sets and 40 mounting said two sets of winding boxes symmetrically with respect to a center of said upper beam;

coupling a first rope to a first of said sets of winding boxes and coupling a second rope to a second of said sets of winding boxes;

providing a lower beam having a plurality of holes and a plurality of second pulleys;

providing a plurality of slats disposed between said upper beam and said lower beam and supported by a plurality of ladder ropes, each of said slats having a plurality of openings formed therethrough;

respectively passing said first and second ropes downwardly through corresponding openings of said slats;

respectively winding said first and second ropes around corresponding pain of said plurality of second pulleys;

respectively passing said first and second ropes upwardly through other corresponding openings of said slates;

respectively winding said first and second ropes over corresponding ones of said rolling shafts and passing respective ends of said first and second ropes through corresponding outlets of said balance strip;

providing a third rope;

passing one portion of said third rope through said rope retaining seat to extend through said upper beam and pass around said first pulley of said pulley box;

passing another portion of said third rope extending from said first pulley back through said upper beam to pass back through said rope retaining seat; and,

joining opposing ends of said third loop together to form a continuous loop and joining said ends of said first and second ropes to said continuous loop, wherein displacement of a length of a first portion of said continuous loop to displace said first and second ropes from said rope retaining seat for raising said lower beam is matched by a corresponding length of another portion of said continuous loop being displaced into said upper beam to thereby maintain a predetermined length of said first portion of said continuous loop substantially unchanged.
